UNITED STATES PATENT OFFICE.

ERNEST ALFRED ALLWOOD, OF ALCESTER, ENGLAND.

NEEDLE FOR SOUND-REPRODUCING INSTRUMENTS.

984,789.

Specification of Letters Patent.

Patented Feb. 21, 1911.

Application filed January 30, 1909. Serial No. 475,244.

To all whom it may concern:

Be it known that I, ERNEST ALFRED ALLWOOD, a subject of the Kingdom of Great Britain, residing at Alcester, in the county 5 of Warwick, England, have invented certain new and useful Improvements in Needles for Sound-Reproducing Instruments, of which the following is a specification.

10 The present invention has relation to needles for use with sound reproducing instruments, and comprises improvements whereby the sound reproducing and vibratory qualities are greatly enhanced.

15 In order that this invention may be clearly understood and more easily carried into practice, reference may be had to the appended explanatory sheet of drawings on which:—

20 Figure 1 is a front elevational view of one form of the present invention. Fig. 2 shows a side view of the needle illustrated in Fig. 1. Fig. 3 illustrates a pointed needle previous to stamping. Fig. 4 shows a modified

25 form of needle subsequent to stamping. Fig. 5 is a vertical section of the needle shown in Fig. 4. Figs. 6, 7 and 8 are further modifications of the improved needle.

30 In carrying the present improvements into effect, the needle is preferably formed from a pointed length of metallic wire A, such wire having one or more raised ridges or rims a' formed by pressing or stamping upon one side of a flattened enlargement 35 as shown by Figs. 5 and 7, or upon both sides

as illustrated in the sectional Figs. 6 and 8, the said ridges or rims being of any suitable section such as semicircular or angular. The metal in the interior of or between the ridges a' is subsequently removed as at a³ 40 Fig. 1 or in cases in which increased rigidity is required, may be retained in the form of a thin diaphragm a², while a fin or feather a⁴ is formed upon the exterior of the rims a'.

The needle may be provided with secondary ridges a⁵ across the face in order to supplement the main ridges a' while one ridge or rim may be formed upon one or each side, or multi-ridges as shown in Figs. 7 and 8 may be used.

Having now described my invention, I declare that what I claim is:—

1. A needle for use with sound reproducing instruments having a flattened enlargement with a raised rim or rims thereon, and a fin or feather exterior edge to the said rim or rims substantially as and for the purpose herein set forth.

2. A needle for use with sound reproducing instruments having a flattened enlargement, a centrally depressed diaphragm with a surrounding rim, and a fin to said rim substantially as and for the purpose herein set forth.

In witness whereof I have hereunto set 65 my hand in the presence of two witnesses.

ERNEST ALFRED ALLWOOD.
